STOOL SEAT

Application filed April 17, 1929. Serial No. 355,838.

This invention relates to new and useful improvements in stool seats or counter chairs of the type used at lunch counters and other places where a simple and durable stool seat is required.

The primary objects of the invention are to simplify the construction and the manufacture of stool seats whereby the seat sections and the back sections can be built separately and then secured together to form a strong and durable structure.

Further objects of the invention are to provide a stool seat having separate seat section and back section, said sections being secured together by means of angle irons arranged adjacent to the outer edges of said sections and having comparatively long arms so as to enable the attachment of said arms to said sections at a plurality of spaced points, thereby providing a rigid construction which will successfully withstand the strains to which the back section is subjected.

Additional objects of the invention are to provide a stool seat of rigid and durable construction which are secured together in a simple and inexpensive manner so as not to detract from the appearance of the chair and wherein the back section is spaced a suitable distance from the seat section so as to provide clearance therebetween and prevent inaccessible corners or crevices which are hard to keep free of dust and crumbs.

With these and other objects in view, our invention consists in certain novel features of construction and arrangement of parts, hereinafter more fully described and claimed, and illustrated in the accompanying drawings, in which—

Figure 1 is a side elevational view of our improved stool seat.

Figure 2 is a front elevational view of same.

Figure 3 is a front elevational view of the back section, partly broken away.

Figure 4 is a top plan view of the seat section, partly broken away.

Figure 5 is an enlarged cross sectional detail view showing the means for attaching the sections together.

Heretofore the back section was generally

secured directly to the rear edge of the seat section either by means of nails or screws or by means of cleats. This construction has not been satisfactory as the seat section did not provide sufficient surface to nail the back section directly thereto and enable said back section to withstand the strains to which it is subjected when in service.

In our present invention we provide simple means whereby the two sections are secured together at points spaced suitable distances apart and wherein said sections are reinforced by suitable angle irons.

Referring by numerals to the accompanying drawings, 10 indicates a seat section and 11 a back section of a stool seat. Each section is preferably made of a piece of board 12 cut to proper shape and having applied thereto a suitable covering 14 which entirely encloses said board and which may be of fabric, leather (genuine or artificial), or other suitable material. The upper side of section 10 and the forward side of section 11 are upholstered or provided with suitable filler material 15.

The board 12 of section 10 is provided in its rear edge with notches 16 which are preferably arranged in the corners of said piece 12. Section 11 which forms the back of the stool seat has its lower edge recessed or curved inwardly as indicated at 17 so as to space the lower edge thereof from the rear edge of section 10. Thus a pair of legs 18 is provided, the width of which is substantially the same as the width of the notches in section 10.

Means for securing the sections together comprises a pair of angle irons 20. Each angle iron consists of a pair of arms 21, preferably disposed at an obtuse angle so as to give the back section a suitable reclining position. These arms 21 are of suitable length and extend approximately more than half way across the sections. Each arm is provided with a series of spaced apertures 22 which coincide with apertures 24 formed in the respective sections. The arms are secured in position to the sections by means of bolts 25 which pass through the aligned apertures and have their heads countersunk in the apertures of the arms and by means of nuts 26 which

are secured on the threaded ends of the bolts and bear against the opposite sides of said sections. As the arms of the angle pieces are of substantial lengths they not only serve to receive the strains and stresses to which the back section is subjected but also to reinforce the sections and particularly the recessed lower end of the back section.

Nuts 26 are preferably countersunk in the 10 respective sections 12 and 12^a. Seat section 10 is secured to a suitable tripod 27 of usual construction, and the latter is mounted in a pedestal or support 28. The arms 21 of angle irons 20 are of substantial lengths and extend 15 more than halfway across the respective sections. This not only distributes the strains throughout the major portion of the sections but also reinforces the latter.

Angle irons 20 are preferably made of malleable iron, thus increasing the strength of the iron and eliminating the danger of breakage thereof under normal conditions.

In constructing the seat, angle irons 20 are attached to one of the sections, such as back 25 section member 12 which is then upholstered. The angle irons 20 are now attached to the other section, in this case seat section member 12^a, and this member is then upholstered. Back section 11 is completely enclosed by covering 14, while seat section 10 (member 12^a) is covered on top and sides and only portion 30 of the underside adjacent to the edges are covered by covering 14. Covering 14 may be secured in position in any suitable manner, 35 such as by tacking a braid 29 to the edges of members 12 and 12^a, respectively.

While we have shown and described herein in the preferred form of our invention, it is obvious that various changes in the construction of our improved stool seat or counter chair can be made without departing from the spirit of our invention.

We claim:

1. In a counter stool construction of the 45 class described, the combination of a seat section having its rear corners notched, a back section having its lower end curved upwardly, thereby forming at each vertical edge a depending leg portion which fits into the respective corner notch, angle irons for securing 50 said legs in position, the horizontal portion of each angle iron being disposed against the underside of the seat section and the upper portion being arranged against the front side 55 of said back section, each of said angle irons being provided with countersunk apertures, and fastening means seated in said apertures and engaging the respective sections for securing said angle iron in position.

2. In a stool construction of the class described, the combination of a seat section 60 provided with rearwardly opening notches, a single piece back section having its lower edge curved upwardly, thereby providing 65 clearance between said sections and forming

at its side edges depending leg portions which fit into said notches, angle irons having their horizontal portions arranged against the underside of said seat section and having their upper portions arranged against the front side of said back section, said portions being provided with a series of spaced countersunk apertures, bolts extending through said apertures and through coinciding apertures formed in the respective sections, the heads of the bolts being arranged in said countersunk apertures flush with the outer faces of the respective portions, and nuts screwed onto the threaded ends of said bolts and disposed in countersunk portions of the apertures of 80 said sections.

In testimony whereof we hereunto affix our signatures this 11th day of April, 1929.

LAWRENCE M. MICHELSON.
JOHN L. HAYNES.
